US0D1105941S

(12) **United States Design Patent** (10) **Patent No.:** **US D1,105,941 S**
(45) **Date of Patent:** **** Dec. 16, 2025**

(54) **FLOW CYTOMETER**

(71) **Applicant:** **Beckman Coulter Biotechnology (Suzhou) Co., Ltd.**, Jiangsu (CN)

(72) **Inventors:** **Jianfei Zheng**, Hangzhou (CN); **Jingzhang Wu**, Suzhou (CN); **Deyi Qiu**, Suzhou (CN); **Yuliang Tang**, Suzhou (CN)

(73) **Assignee:** **Beckman Coulter Biotechnology (Suzhou) Co., Ltd.**, Suzhou (CN)

(**) **Term:** **15 Years**

(21) **Appl. No.:** **29/867,853**

(22) **Filed:** **Nov. 10, 2022**

(57) **CLAIM**

An ornamental design for a flow cytometer as shown and described.

DESCRIPTION

FIG. 1 is a perspective view of a first embodiment of the flow cytometer;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of the flow cytometer;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is another perspective view thereof, in an alternate position; and,

FIG. 16 is another perspective view thereof, in another alternate position.

The portions depicted in broken lines form no part of the claimed design.

1 Claim, 16 Drawing Sheets
